UNITED STATES PATENT OFFICE

WILLIAM B. MCGILL, OF DORMONT, PENNSYLVANIA, ASSIGNOR TO NEON SIGNAL SERVICES, INC., OF PITTSBURGH, PENNSYLVANIA, A CORPORATION OF PENNSYLVANIA

TRAFFIC SIGNAL

Application filed October 16, 1929. Serial No. 399,979.

My invention relates to signals for controlling and directing traffic, and one embodiment thereof is designed particularly for the warning of vehicles and pedestrians approaching an arterial highway or boulevard.

Although numerous forms and modifications of warning devices and traffic signals have been suggested, the problem of controlling traffic so as to avoid the ever increasing number of disastrous accidents is yet unsolved. I have solved this problem by providing a signal for intersections of branching highways with boulevards, such that the traffic approaching the through thoroughfare will be positively warned of that fact so that proper precautions may be taken.

In order to accomplish this result, I employ a luminous tube to which I give the shape of the letters of a word of warning as "Stop". I also provide an auxiliary indication in the form of a stencil plate, which is adapted to be illuminated by the luminous tube. In order to make the latter more effective, I form letters on the stencil plate for cooperating therewith. I also make provision for illuminating the outline of the signal housing so as to afford a more commanding signal warning. Other novel features contemplated by my invention include improvements in the design and construction of the signal housing, the closure means therefore, and means for limiting the intensity of illumination of the signal so as to avoid unnecessary annoyance to pedestrians and residents of the neighborhood in which the signal is located. The invention will be fully described in connection with the accompanying drawings illustrating a present preferred embodiment thereof, and novel features thereof will be pointed out definitely in the appended claims. The embodiment herein described is in nowise to limit the scope of the invention which is defined solely by the claims.

In the drawings,

Figure 1 is a front elevational view of one embodiment of my invention;

Figure 2 is a similar view with the signal housing closure opened;

Figure 3 is a section along the plane of

line III—III of Fig. 1, and shows the signal housing supported on a suitable holder;

Figure 4 is a partial sectional view along the plane of line IV—IV of Fig. 1;

Figure 5 is a view similar to Fig. 4, showing a modified form;

Figures 6, 7, and 8 are partial views illustrating details of the present embodiment.

Referring in detail to the drawings, and particularly to Figs. 1 through 3, the illustrated embodiment of my invention consists of a hemispherical sheet-metal housing 10. A back casting 11 is suitably formed to receive the housing 10 and is provided with depending lugs 12 for supporting the housing. The housing 10 is secured to the back casting 11 by means of a clamping plate 13 and a nipple 14 on which clamping nuts 15 are threaded. The nipple 14 also provides a conduit for the entrance of electrical connections to the luminous tube for illuminating the housing, as will be described later.

The housing 10 is provided with lugs 16 which afford a hinged support for a closure 17 for the front wall of the housing. This closure consists of a rim 18 having rearwardly extending lugs 19 for cooperating with the lugs 16. A hinge pin 20, serves to provide a pivotal support for the closure 17. The rim 18 has an annular groove 21 which receives the edge of the housing 10, a gasket being placed within the groove to form a water-tight joint.

A recess 22 is formed in the rim 18, and a glass window 23 is seated therein and cemented thereto. It will be observed that the depth of the recess 22 is less than the thickness of the window 23. The purpose of this arrangement will be pointed out hereinafter. A stencil plate 24, bearing indicia-forming cutouts 25, is secured to the rim 18 by screws 26. The plate 24 does not engage the window 23 directly, but is spaced therefrom by means of spacing collars 27 on the screws 26. This arrangement permits the drainage of rain water from behind the stencil plate 24.

A shoulder 28 is formed in the housing 10 to receive a partition wall 29. The wall is secured in place by means of retaining lugs 30, but may be removed by a slight rotation so

that cutouts 31 in the wall are alined with the lugs 30. In order to provide a close fit of the wall in the shoulder, the former may be pressed out slightly as at 32, so that it engages the lugs 30 tightly. Handles 33 facilitate manipulation of the partition wall 29.

On the front face of the wall, a luminous tube 34 is supported behind appropriate cutouts in the stencil plate 24. The tube 34 is formed into a traffic warning word, such as "Stop", the portions of the tube between the letters being obscured by blocking-out paint applied to the front surface of the tube only, as indicated at 35. The cutouts in the stencil plate 24 also serve to isolate the portions of the tube behind the letters of the stencil plate. Prism reflectors 36 are secured to the housing 10 above and below the luminous tube 34 by means of clips 37 on the partition wall 29. These reflectors direct light from the luminous tube 34 outwardly of the housing 10 through the cutouts 25 in the stencil plate 24.

By reason of the thickness of the window 23 relative to the depth of the recess 22, in which it is seated, a certain amount of light passes by internal reflection in the window 23 to the space 18a between the outer edge of the stencil plate 24 and the inner edge of the flange on the rim 18. This reflected light provides an illuminated outline for the signal housing and greatly increases its visibility and effectiveness in controlling traffic. The luminous tube gives a positive and commanding direction which stands out even in daylight, and, as a result, the necessity of exercising proper precautions is more emphatically brought home to the motorist and pedestrian.

The partition wall 29 also serves as a support for a motor driven flasher 38 and a transformer 39 for supplying current of suitable voltage to the luminous tube 34. If a steady indication is desired, the flasher 38 may be omitted, but it is generally found that an intermittent flashing signal produces better results than a warning sign illuminated constantly.

The signal housing 10 may be supported by means of the lugs 12 on a laterally-extending rod 40, which may be attached to any type of support. Since the signal is generally mounted along arterial highways or streets at the curb, I prefer to employ a clamp 41 for supporting the housing 10 and rod 40 from a vertical support such as a telephone or telegraph pole 42. The clamp 41 consists of three members, 43, 44, and 45. The members 43 and 45 are merely semi-circular clamping straps, while the member 44 is an integral double-face clamp which has a face 46 for engaging a vertical support, such as the post 42, and a face 47 for engaging a laterally-extending support, such as the rod 40. The housing 10 may be supported on the post 42 by applying clamping members 43 and 44 to the latter and then clamping the rod 40 be-

tween the clamping strap 45 and the face 47 of the clamping member 44.

In Figures 2 and 4, the details of the mechanism provided for maintaining the closure 17 in engagement with the housing 10 may be observed. Lugs 50 are formed on the rim 18 and a locking arm 51, having a handle 52 is pivotally secured to said lugs. Cooperating lugs 53 on the housing 10 are fitted with adjustable studs 54 which form a fulcrum for the arm 51. When the handle 52 is forced toward the housing 10, the engagement of the arm 51 with the studs 54 draws the closure 17 tightly into engagement with the housing. A staple 55 on the housing 10 permits the handle 52 to be secured thereto by means of a padlock 56, for example.

When the traffic-controlling signal herein described is to be mounted in residential districts, it will be desirable to limit the intensity of illumination thereof to prevent annoyance to occupants of nearby residences by reason of an unnecessarily bright illumination. I provide means in the form of vertically-extending angularly-disposed louvres 60 (Fig. 5) to prevent the emission of direct rays from the signal, except onto the highway. These louvres 60 are integral with a frame 61, which is secured to the rim 18 of the closure 17 between the window 23 and the luminous tube 34. The louvres are simply strip-like slats extending vertically in the housing 10 and bent at a slight angle to the axis thereof. They may be formed integral with the plate 61, as stated, or they may be formed separately and secured thereto either rigidly or adjustably after the manner of the ordinary window shutter. The louvres are given a dull reflecting surface such as is provided by a coat of aluminum paint. The angle at which the louvres 60 are disposed may be chosen so that the direct light radiated by the luminous tube will be confined to a certain area and so that the signal will be visible from other points only by reflected light. In order to assist this restricting and confining action on the light rays, I may utilize half channels 62 (Fig. 6) conforming to the shape of the letters of the stencil plate. These channels tend to reflect the light into the area where it is desired and to prevent its being directed toward other points. The louvres and channels do not prevent the signal from being seen from the sides of the street so that its effect in warning pedestrians is not diminished. Direct rays from the luminous tube are, however, confined to the motor traffic lanes and do not cause annoyance to residents in the vicinity.

Figures 7 and 8 illustrate a modified form of locking device for the closure 17. The handle 52 of the arm 51 has its outer end turned at right angles for cooperation with a rotatable stud 64 having a wing 65. The stud 64 is secured to the housing 10 and when

turned to the position illustrated in Fig. 7, the wing 65 overlies the handle 52 and remains in the illustrated position. A padlock 56 may be employed to lock the closure as shown in Fig. 7. When the stud 64 is turned at right angles, as shown in Fig. 8, the handle 52 may be retracted and the closure 17 opened. Cam faces may be formed on co-operating surfaces of the handle 52 and the wing 65 to aid in clamping the closure tightly to the housing.

A number of advantages characterize the signal herein described and render it an outstanding improvement over similar devices known in the prior art. In the first place, the luminous tube type of sign is well known to be much more effective and much more readily visible than signs illuminated by incandescent lamps. The current consumption of this type of sign is much less than the incandescent lamp type, and its control and regulation involves no special difficulties.

The warning signal utilizes not only the light emitted by the luminous tube through the stencil plate, but also the light which radiates rearwardly from the tube. This light is redirected through the stencil plate and through the annular peripheral space forming a frame for the signal, by means of suitable reflectors.

The housing 10 is a unitary structure and by reason of the gasket between it and the rim 18, a water-tight structure is the result, the window 23 being tightly cemented to the rim 18. In addition to the foregoing advantages, I have provided means for limiting the zone of maximum intensity of illumination of the signal to avoid unnecessary annoyance and have disclosed several improvements in the structure of the signal housing. Among these, may be noted that a strong and rigid structure is provided by clamping the housing 10 between the back casting 11 and the clamping plate 13. The housing 10 may be adjusted for position in every direction. In case the supporting pole 42 is not absolutely vertical, the housing 10 may be rotated axially about the nipple 14. In addition, the housing 10 may be adjusted about the axis of the tube 40 and also about the axis of the pole 42. The housing may also be shifted vertically of the pole 42 and laterally of the tube 40, so that it may be properly positioned for any particular installation.

While I have illustrated and described a present preferred embodiment of my invention, it is to be understood that it may be otherwise embodied within the spirit of the invention and the scope of the appended claims.

I claim:

1. In a traffic signal, the combination with a housing, a cover for the housing having cut-outs therein forming traffic directions, a luminous tube disposed adjacent certain of

said cutouts and conforming thereto in shape, adapted to illuminate the latter by direct light, of reflecting means in the housing for illuminating others of said cutouts by light radiated from said tube and reflected through said cutouts by said means.

2. In a traffic signal, the combination with a housing, one wall thereof having cutouts forming traffic directions, a luminescent tube conforming in shape to certain of said cutouts, of means for reflecting a portion of the light radiated by said tube through others of said cutouts.

3. A signal device comprising a housing having a light source therein, a cover therefor including a rim having a recess therein, and a glass plate of thickness greater than the depth of said recess cemented therein, and a stencil plate secured to said rim in spaced relation to said glass plate.

4. A signal device comprising a housing having a light source therein, a cover therefor including a rim having a recess therein, and a glass plate of thickness greater than the depth of said recess cemented therein, and a stencil plate secured to said rim.

5. An indicia-bearing cover for a sign housing containing a light source including a rim secured to the housing, a glass plate mounted in said rim so that the surface of the plate extends beyond the adjacent edge of the rim, and a stencil plate overlying said glass plate.

6. A signal device comprising a housing, a transparent wall therefor and indicia-forming means cooperating therewith, a light source in said housing and a series of louvres between said source and said means for preventing transmission of light rays in predetermined directions, and light-directing means on said indicia-forming means.

7. A signal housing including a rim, a transparency therein, and a stencil overlying the transparency and having its face and edge spaced from said rim.

8. A signal housing having a rim and a stencil positioned over an opening therein, said stencil having its edges spaced inwardly of said rim to provide a luminous outline for said signal.

9. A signal housing including a rim having an annular recess, a stencil shaped to fit in said rim and dimensioned to leave a peripheral space between said rim and the stencil.

10. A sign including a housing, a stencil therefor having a plurality of indicia, a luminous tube behind said stencil conforming in shape to certain of said indicia, and means for illuminating the other indicia by light reflected from said tube.

11. In a sign, the combination with a housing, stencil cutouts in one wall of the housing forming sign characters, of a luminous tube within the housing adjacent certain of said

130

cutouts and conforming thereto in shape, for illuminating said last mentioned cutouts by direct rays and the other cutouts by reflected rays.

5 12. In a sign, a housing having one wall provided with light-transmitting sign characters, a luminous tube within the housing adjacent said characters and conforming in shape to some of them to illuminate them by direct rays, and means for reflecting light from the tube through the other characters.

10 13. The combination in a sign, with a housing having a wall provided with light-transmitting sign characters, of a distributed light source conforming in shape to said characters and closely adjacent thereto, and parallel louvers between the source and the characters for intercepting the diffuse rays from said source without obstructing the rays emanating therefrom substantially perpendicular to said wall.

15 14. The combination, in an illuminated sign, with a housing having an open wall closed by a transparency, and a stencil plate having a plurality of indicia cut therein overlying said transparency, of a luminous tube in said housing adjacent one of said indicia and conforming thereto in outline, and means for illuminating the other indicia by light emitted from said tube.

20 15. In a sign, the combination with a distributed light source such as a luminous tube, and a stencil plate having cutouts therein, of vertical louvers between said source and said plate to prevent the blurring of the illumination of said cutouts by diffused rays and to limit the zone of visibility thereof.

In testimony whereof I have hereunto set my hand.
